(57) CLAIM

The ornamental design for a latch for a storage container, as shown and described.

DESCRIPTION

FIG. 1 is a front perspective view of a latch for a storage container;

FIG. 2 is a front view thereof (the rear view is identical to the front view);

FIG. 3 is a top view thereof; and,

FIG. 4 is a right side view thereof (the left side view is identical to the right side view).

The phantom lines in FIGS. 1-4 are for illustrative purposes only and do not form part of the claimed invention.
